UNITED STATES PATENT OFFICE

1,999,629

DETERGENT

Peter Friesenhahn, Berlin-Grunewald, Germany,
assignor, by mesne assignments, to "Unichem"
Chemikalien Handels A.-G., Zurich, Switzerland,
a corporation of Switzerland

No Drawing. Application December 14, 1929,
Serial No. 414,223. In Germany August 8,
1929

3 Claims. (Cl. 87—5)

It is a known fact that alkaline phosphates such as described for example in British Patent No. 253,554, accepted September 14, 1927, and particularly tri-sodium phosphate or sodium orthophosphate possess an extraordinarily strong solvent power for all kinds of fats and oils in a degree rendering them suitable as fat solvents and cleaning agents, particularly in the iron industry, 5 in automobile factories, etc. The above mentioned salts however, show a disadvantage inasmuch as their effects may fully be brought out only if the objects to be cleaned as for instance metal parts etc. be boiled in the watery solutions 10 of those salts. Nor do these salt solutions possess any lather properties thereby differing in this regard very materially from the most commonly used soap bodies employed as cleaning agents.

Certain discoveries resulted in the preparation 20 of extraordinarily valuable compounds in which the above mentioned phosphates, particularly the tri-sodium phosphate were more or less brought together with the sulphonates of organic bodies. The mixture for instance containing besides 75% 25 of tri-sodium phosphate, 25% tetra-hydronaphthalenesulphonate of sodium, yields strong lathering solutions that even at ordinary temperatures, produce cleansing effects to the fullest measure. Moreover, they yield a not inconsiderable wetting- 30 out property, although neither ingredient used by itself has satisfactory wetting-out properties. The above mentioned salt compounds therefore, may be used to advantage not only like the phosphates in the iron industry, but going beyond this 35 point, also particularly in the textile industry.

I also may use and substitute for the above mentioned tetra-hydronaphthalenesulphonate of sodium, other salts of this sulpho-acid, as for instance the salt of potassium, of ammonium or salts of organic bases. However, I also may substitute in their place the corresponding salts of other sulphonic acids as for instance the naphthalenesulphonic acid and its salts, the sulphuric acid ester of higher molecular alcohols, Turkey-red oil, etc. The percentage also of the individual ingredients as contained in the mixture may range within varying limits. For instance I get an extraordinarily valuable product when bringing together phosphate holding 50% of tri-potassium with a 50% octadecylalcoholsulphuric acid ester neutralized through ammonia. 15

I claim:

1. A detergent having lathering and wetting-out properties comprising 50% of tripotassium 20 phosphate and 50% of the ammonium salt of the sulphuric acid ester of octadecyl alcohol.

2. A detergent having lathering and wetting-out properties comprising in combination an alkali metal phosphate and the sulphuric acid 25 ester of a high molecular primary aliphatic fatty alcohol having lathering and detergent properties approximating those of the sulphuric acid ester of octadecyl alcohol.

3. A detergent as defined in claim 2 wherein 30 the alkali metal phosphate and the sulphuric acid ester are present in a ratio of 3 to 1.

PETER FRIESENHANN.
